(57) **CLAIM**

I claim the ornamental design for a display screen or portion thereof with color graphical user interface, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a display screen or portion thereof with color graphical user interface showing an embodiment of my new design; and,

FIG. 2 is a front view of a display screen or portion thereof with color graphical user interface showing another embodiment of my new design.

The dashed broken lines around the figures show a display screen or portion thereof that form no part of the claimed invention.
